4 Claims. (Cl. 263—19)

1

This invention relates to heaters for enclosed spaces. The general object of the invention is to provide a heater, preferably intended to be located within the enclosed space, which will supply to that space a mixture of hot gaseous products of combustion and air of which at least a portion is drawn from outside that space, preferably from out-of-doors. The invention is particularly useful and is hereinafter described as embodied in tobacco-barn heaters; but it will be understood that it may be embodied in heaters for supplying a mixture of hot air and gaseous products of combustion to an enclosed space of any kind used for any purpose, which is to be heated, temporarily or for an extended period of time to a high temperature, say 150° to 200° F. When the invention is embodied in a tobacco-barn heater, it not only supplies to the barn a mixture of hot air and gaseous products of combustion, but will produce proper circulation within the barn of the hot air and gases so that tobacco hung up within the barn will be rapidly, efficiently and uniformly cured at desired temperature without fire risk.

The fuel employed in the embodiments of the invention hereinafter described is preferably oil, but artificial or natural gas may be used. The air needed for combustion of the fuel, and the circulation of the hot products of combustion and heated air, are supplied by an electrically-driven fan. Not only is out-of-doors air supplied to the heater by the fan, but the fan also draws air from within the barn and supplies it to the heater. Although the highest temperature of the air and gaseous products of combustion supplied by the heater may be as high as perhaps 1200° F., all danger of fire due to tobacco leaves falling on the heater is eliminated by reason of the fact that all of the parts of the heater which carry the hot gaseous products of combustion and air are enclosed within casings and pipes through which cooler air is circulated.

The various advantages of the heater will appear from the following description of its construction, taken in connection with the accompanying drawings, in which Fig. 1 is a side elevation, partly in section, of a heater embodying the invention located within a tobacco barn; Fig. 2 is a sectional elevation of another form of the heater embodying the invention; Fig. 3 is a plan view of the heater shown in Fig. 2, the walls of the barn being indicated in section; Fig. 4 is a sectional elevation of still another form of heater embodying the invention; and Fig. 5 is a fragmentary view of a portion of the wall of the combustion chamber, showing the small holes therein.

The embodiment of the invention illustrated in Fig. 1 will first be described. In that figure, the heater is shown as located on the floor 10 of a tobacco barn in which the tobacco leaves 12 to be cured are shown suspended in a usual way from sticks 14 resting on supports 16. A portion of one of the walls of the barn is indicated at 18, in order to make clear that out-of-doors air is drawn through a pipe 20 into the heater about to be described. As will be apparent from Fig. 1, the heater includes a suitably supported motor 22 enclosed within a casing 24 into which outdoor air passes through the pipe 20. Supported on the shaft of the motor 22 and driven thereby is a fan 26 (of any well-known type) located within a suitable fan casing 28. Arranged above the fan casing 28 is a circular outer casing 30 within which is supported a combustion chamber 32 the construction and functioning of which will be hereinafter described. Mounted in the bottom of the combustion chamber 32 is a fuel nozzle 34; and an ignition device, such as a spark plug 36, is mounted in the combustion chamber, as shown. It will be noted that the casing 30 is spaced away from the combustion chamber 32, thereby providing an annular space through which air passes from the fan 26. Cooperating with the top of the combustion chamber 32 is an inner casing or manifold 40 which receives from the combustion chamber 32 the hot gaseous products of combustion and diluting air mixed therewith. Connected to the manifold 40 are a plurality of distributing pipes 42 which extend outwardly from the manifold and carry the mixture of hot air and gaseous products of combustion to the downwardly directed ends 44 of the distributing pipes 42. A casing 46 surrounds the manifold 40 and is supported on the top of the casing 30 which surrounds the combustion chamber 32. An annular space is provided between the casing 46 and the top of the casing 30, through which air supplied by the fan 26 may flow into the space within the manifold casing 46. Connected to the top of the manifold casing 46 is a pipe 50 which extends upwardly and outwardly and is connected to a downwardly extending pipe 52 communicating with a horizontally arranged pipe 54 leading to the fan casing 28. The pipe 54 is preferably provided with an extension 56 containing a damper 58 by which the admission of barn air to the pipe 54 may be regulated. Encasing pipes 60 extending from the manifold casing 46 surround the distributing pipes 42, thereby providing annular passages between the distributing pipes 42 and the encasing pipes 60.

Through these annular passages flow barn air which enters the encasing pipes 60 at their hooded ends 62 surrounding the downwardly extending ends 44 of the pipes 42. For a purpose hereinafter explained, the encasing pipes 60 are preferably provided with openings which may be located at various places and in Fig. 1 are indicated at 64 near the points where the encasing pipes 60 are connected to the manifold casing 46. The manner in which the distributing pipes 42 and their encasing pipes 60 extend outwardly from the heater will be apparent from Fig. 3 although that figure is a plan view of the embodiment of the invention particularly illustrated in Fig. 2 and hereinafter described. Fuel oil or gas is supplied to the fuel nozzle 34 through the pipe 66 from any suitable oil pump (not shown) which may be driven by the motor 22 or otherwise; and the spark plug 36 is connected by a wire 68 to any suitable and well-known ignition device which is not shown since it forms no part of the present invention. The particular construction of the combustion chamber 32 also forms no part of the present invention, but will be hereinafter described with the aid of Figs. 4 and 5 in which the combustion chamber is shown on a larger scale than in Fig. 1.

The manner in which the air and gaseous products of combustion circulate through the heater shown in Fig. 1 will be apparent from the various arrows applied to that figure. Out-of-doors air, drawn into the heater through the pipe 20 by the motor-driven fan, cools the motor sufficiently to prevent excessive heating of it. The air supplied by the fan passes upwardly through the annular space between the casing 30 and the combustion chamber 32, and some of this air flows and seeps (as hereinafter described) into the combustion chamber 32, and some of this air passes upwardly, through the restricted opening between the top of the casing 30 and a lip extending downwardly from the manifold 40 into the space within the manifold casing 46. The air entering the combustion chamber 32 is sufficient not only to support substantially complete combustion of the fuel, but to provide an excess of air which mixes with the gaseous products of combustion and passes upwardly out of the top of the combustion chamber 32 into the manifold 40 along with the gaseous products of combustion. In this way, the temperature of the mixture of gaseous products of combustion and air entering the manifold 40 is prevented from rising to an excessive value. In practice, this mixture of air and gaseous products of combustion may be in the neighborhood of 1200° F. Owing to the suction exerted by the fan 26 through the pipes 54, 52 and 50, a flow of air is induced from the top of the manifold casing 46, with the result that air is drawn in through the hoods 62 into the annular spaces between the distributing pipes 42 and the encasing pipes 60; and air is also drawn in through the openings 64 in the encasing pipes 60. This suction effect of the fan may be regulated by means of the damper 58. Thus it will be apparent that all of the parts of the heater, which are raised to high temperatures by contact with the mixture of gaseous products of combustion and air emerging from the combustion chamber 32, are surrounded by the casings 30 and 46 and by the encasing pipes 60. Therefore, there will be no fire risk resulting from a tobacco leaf dropping on any of the parts of the heater.

The form of the invention illustrated in Figs. 2 and 3 will now be described. It will be noted that this embodiment of the invention differs from the embodiment illustrated in Fig. 1 by the fact that the pipes 50, 52 and 54 (which in Fig. 1 connect the top of the manifold casing 46 with the fan casing) are omitted and the top of the manifold casing is closed. Therefore, the functioning of the heater illustrated in Figs. 2 and 10 3 differs from the functioning of the heater shown in Fig. 1, in that air flows from the manifold casing outwardly instead of inwardly through the annular spaces between the distributing pipes and the encasing pipes. In Figs. 15 2 and 3, like parts are referred to by the same reference characters as those employed in Fig. 1, and a detailed description of those parts is unnecessary. The cover which closes the top of the manifold casing 46 in Fig. 2 is shown at 92; and 20 it will be noted that the arrows, which indicate the direction of air flow through the annular spaces between the distributing pipes 42 and the encasing pipes 60, point in a direction opposite to the arrows in those spaces in Fig. 1. 25 The manner in which the air and gaseous products of combustion circulate through the heater shown in Fig. 2 will be evident from the various arrows applied to that figure. In the heater of Fig. 2, the fan draws air from out-of-doors through the pipe 20 in cooling engagement with the motor 22; and the fan also draws in 30 barn air as indicated by the arrows at the left end of the fan. The air thus supplied by the fan passes upwardly through the annular space between the casing 30 and the combustion chamber 32. Some of this air flows and seeps into the combustion chamber 32 where it supports the combustion of the fuel and also provides an excess of air which mixes with the gaseous products 35 of combustion; and this mixture passes upwardly out of the top of the combustion chamber 32 into the manifold 40. The remainder of the air supplied by the fan passes upwardly, through the restricted opening between the top of the casing 30 and a lip extending downwardly from the manifold 40, into the space within the manifold casing 46, as shown by the arrows in Fig. 2; and 40 this air flows outwardly through the annular spaces between the distributing pipes 42 and encasing pipes 60, along with mixed barn air which enters the encasing pipes 60 through the openings such as those shown at 64. That is, in the heater of Fig. 2, the air flowing through the annular spaces between the distributing pipes 42 45 and the encasing pipes 60 passes out of the hoods (indicated at 62 in Fig. 1) instead of being drawn in through those hoods as is the case in the heater of Fig. 1. In the heater of Fig. 2 (as in the heater of Fig. 1) all of the parts of the heater which are raised to a high temperature by the hot mixture of air and combustion gases supplied from the combustion chamber are surrounded by the casing 30, the manifold casing 46 and cover 92, and by the encasing pipes 60, thereby 50 eliminating any fire risk resulting from a tobacco leaf dropping on any parts of the heater.

The heater embodying the invention which is illustrated in Fig. 4 will now be described; and the construction and functioning of the combustion chamber, which is the same in all three illustrated embodiments of the invention, will be later explained. In the heater of Fig. 4, the air is supplied by the fan 76 which is driven by the motor 78, as in the heater of Fig. 2. The heater of 75 Fig. 4 differs from the heaters of Figs. 1 and 2

principally in the relative locations of the fan, combustion chamber and manifold. In the heaters of Figs. 1 and 2, the combustion chamber 32 and its surrounding casing 30 are arranged between the fan 26 and the manifold 40 and its surrounding casing 46, with the result that the air supplied by the fan flows through the casing 30 surrounding the combustion chamber 32 on its way to the casing surrounding the manifold. In the heater of Fig. 4, however, the manifold 80 and its surrounding casing 82 are arranged between the fan 76 and the combustion chamber 84 (hereinafter described) and its surrounding casing 91, with the result that the air supplied by the fan 76 passes through the manifold casing 82 on its way to the casing 91 surrounding the combustion chamber 84. It will also be noted that in the heater of Fig. 4 the combustion chamber 84 is inverted (in comparison with the arrangement shown in Figs. 1 and 2) with the result that the gaseous products of combustion and diluting air mixed therewith flow downwardly (instead of upwardly) from the combustion chamber 84 into the top of the manifold casing instead of into the bottom of the manifold casing as in the heaters of Figs. 1 and 2. Referring now to the details of construction of the heater shown in Fig. 4, it will be apparent that a pipe 88 extends upwardly from the fan casing and communicates with a casing 89 which at its top is associated with the manifold casing 82; and that a casing 91 which surrounds the combustion chamber 84 and is provided with a top cover 92, is mounted on the top of the manifold casing 82. Extending outwardly from the manifold 80 are the distributing pipes 93. As in the heater of Figs. 1 and 2, the distributing pipes 93 are surrounded by encasing pipes 94 which are secured to the manifold casing 82. As will be apparent from Fig. 4, the construction of the manifold casing 82, where the encasing pipes 94 are connected to it, is such that a restricted annular opening is provided through which air flows from the manifold casing 82 into the spaces between the pipes 93 and 94, as shown by the arrows. A cylindrical sheet metal wall 96 is mounted between the casing 91 and the combustion chamber 84, for a purpose later described. As in the heaters of Figs. 1 and 2, the combustion chamber 84 of the heater shown in Fig. 4 is provided with a fuel nozzle 100 connected to a fuel supply pipe 102; and is also provided with a spark plug 104 which is connected by a wire 106 to any suitable and well known ignition device.

The manner in which the air and gaseous products of combustion circulate through the heater shown in Fig. 4 will be evident from the various arrows applied to that figure. As in the case of the heater of Fig. 2, the motor driven fan shown in Fig. 4 supplies both out-of-doors and barn air to the heater. This air flows upwardly through the pipe 88 and casing 89 into the manifold casing 82 from which some of the air flows through the restricted annular openings into the spaces between the pipes 92 and 94, and the rest of the air flows upwardly through the annular space between the casing 91 and the wall 96, and then over the top of the wall 96 and into the annular space between the wall 96 and the combustion chamber 84, from which this part of the air flows and seeps into the combustion chamber 84 as hereinafter described. The mixture of the gaseous products of combustion and diluting air passes from the combustion chamber 84 into the manifold 80 and then outwardly through the distributing pipes 75

93. It will be understood that the distributing pipes 93 at their outer ends may be provided with downwardly extending portions of the kind shown at 44 in Figs. 1 and 3; and the outer ends of the encasing pipes 60 may be provided with hoods such as those shown at 62 in Fig. 1. In the heater of Fig. 4 (as in the heater of Figs. 1 and 2) all of the parts of the heater which are raised to high temperatures by the mixture of air and gaseous products of combustion supplied by the combustion chamber 84 are surrounded by cooler air which is supplied by the motor-driven fan, thus eliminating any fire risk if a tobacco leaf falls on any part of the furnace. 10 The construction of the combustion chamber employed in the three illustrated embodiments of the invention will now be described. Since this combustion chamber is novel in construction and may not be claimed in the present application, it is the subject of a separate patent application, Serial No. 73,411, filed January 28, 1949. The structure of the combustion chamber will be described with the aid of Fig. 4 because it is there shown on a larger scale than in Figs. 1 and 2; and Fig. 5 will also be referred to. From Figs. 4 and 5 it will be apparent that the entire cylindrical portion of the combustion chamber is made of sheet metal which is perforated throughout its area with a large number of small holes 110 shown in Fig. 5. The primary purpose of these small holes 110 is to permit air to seep through the wall of the combustion chamber and provide on its inside surface a layer or cushion of air which I have discovered serves 20 the highly useful purpose of preventing the formation of a carbonaceous deposit on the inside of the combustion chamber. These small holes 110 also result in a cooling of the combustion chamber due to the air seeping through them. 25 To the best of my knowledge and belief, it is novel to use such perforated sheet material for the making of a combustion chamber; and I believe that I am the discoverer of the highly beneficial results achieved by the use of such perforated sheet material in the making of a combustion chamber. Furthermore, I have discovered that the size of the holes 110 in the wall of the combustion chamber has an important bearing upon the results and advantages achieved. 30 I have found that the best results are obtained by employing for the making of the wall of the combustion chamber 22 gauge, type 310 or 446 stainless sheet steel which is perforated with holes having a diameter of approximately .036 35 of an inch and arranged with approximately 270 holes to the square inch. It will however be understood that gauge of the sheet steel, the diameter of the holes and the number of holes per square inch may vary somewhat from the figures just given, without sacrificing the advantages of my novel combustion chamber. The important thing is to make these holes 110 so small and to arrange them so closely to one another that air will seep through them into the combustion chamber and will provide a cushion or layer of air on the inside of the wall of the combustion chamber. The much larger holes 40 112 (shown in Fig. 4) in the cylindrical wall of the combustion chamber 84, serve to admit to the combustion chamber the air necessary to adequately support combustion of the fuel, and additional air to dilute the gaseous products of combustion which is considered desirable in the heaters described in this application. 45 While the invention has been described as

embodied in tobacco-barn heaters, it will be understood (as mentioned at the beginning of this specification) that it may be embodied in heaters for supplying a mixture of hot air and gaseous products of combustion to an enclosed space of any kind. Of course, when the heater is used for some purposes, the distributing and encasing pipes may be omitted, for which reason these elements are not included in some of the claims hereto appended.

What is claimed is:

1. A heater for supplying hot air to an enclosed space within which said heater is located, comprising a cylindrical combustion chamber closed at one end and open at the other end and having in its cylindrical portion holes for admitting air, a casing surrounding said combustion chamber and spaced therefrom, a manifold directly connected to the open end of said combustion chamber to receive therefrom hot air and gaseous products of combustion, distributing pipes connected to and extending from said manifold and opening into said enclosed space to receive the hot air and gaseous products of combustion from said manifold and discharge same into said enclosed space, a casing surrounding and spaced from said manifold and surrounding and spaced from said distributing pipes, and a fan connected and arranged to supply air to the space within the said casing which surrounds said combustion chamber, encasing pipes connected to and extending from the said casing which surrounds said manifold and surrounding and spaced from said distributing pipes, and a fan connected and arranged to supply air to the space within the said casing which surrounds said combustion chamber and to the holes in the combustion chamber and also to the space within the said casing which surrounds said manifold, a first air inlet to said fan comprising a pipe leading to said fan from outside said enclosed space, a motor located in said pipe substantially in line with the axis of said pipe and coupled to drive said fan, and a second air inlet to said fan communicating with said enclosed space to effect recirculation of heated air discharged from said distributing pipes into said enclosed space.

2. A heater for supplying hot air to an enclosed space within which said heater is located, comprising a fan, a casing arranged to receive air from said fan, a cylindrical combustion chamber supported within said casing and closed at one end and open at the other end and having in its cylindrical portion holes for admitting air, a manifold directly connected to the open end of said combustion chamber to receive therefrom hot air and gaseous products of combustion, distributing pipes connected to and extending outwardly from said manifold and opening into said enclosed space to receive the hot air and gaseous products of combustion from said manifold and discharge same into said enclosed space, a casing surrounding and spaced from said manifold and communicating with said casing within which said combustion chamber is mounted, encasing pipes connected to and extending from said manifold casing and surrounding and spaced from said distributing pipes, a first air inlet to said fan comprising a pipe leading to said fan from outside said enclosed space, a motor located in said pipe substantially in line with the axis of said pipe and coupled to drive said fan, a second air inlet to said fan communicating with said enclosed space to effect recirculation of heated air discharged from said distributing pipes into said enclosed space, and a duct connecting said manifold casing with the

intake side of said fan; whereby combustion air is supplied by said fan to the space between said first mentioned casing and said combustion chamber and also to the space between said manifold and its casing, and cooling air is drawn by said fan through the annular spaces between said distributing and encasing pipes and into said manifold casing.

3. A heater for supplying hot air to an enclosed space within which said heater is located, comprising a cylindrical combustion chamber closed at one end and open at the other end and having in its cylindrical portion holes for admitting air, a casing surrounding said combustion chamber and spaced therefrom, a manifold directly connected to the open end of said combustion chamber to receive therefrom hot air and gaseous products of combustion, distributing pipes connected to and extending from said manifold and opening into said enclosed space to receive the hot air and gaseous products of combustion from said manifold and discharge same into said enclosed space, a casing surrounding and spaced from said manifold and communicating through a restricted opening with the said casing which surrounds said combustion chamber, encasing pipes connected to and extending from the said casing which surrounds said manifold and surrounding and spaced from said distributing pipes, and a fan connected and arranged to supply air to the space within the said casing which surrounds said combustion chamber and to the holes in the combustion chamber and through the restricted opening into the space within the said casing which surrounds said manifold and out through the annular spaces between said distributing and encasing pipes, a first air inlet to said fan comprising a pipe leading to said fan from outside said enclosed space, a motor located in said pipe substantially in line with the axis of said pipe and coupled to drive said fan, and a second air inlet to said fan communicating with said enclosed space to effect recirculation of heated air discharged from said distributing pipes into said enclosed space.

4. A heater for supplying hot air to an enclosed space within which said heater is located, comprising a fan, a casing arranged to receive air from said fan, a cylindrical combustion chamber supported within said casing and closed at one end and open at the other end and having in its cylindrical portion holes for admitting air, a manifold mounted between the fan and combustion chamber within said casing and directly connected to the open end of said combustion chamber to receive therefrom hot air and gaseous products of combustion, distributing pipes connected to and extending outwardly from said manifold through the wall of the first mentioned casing and opening into said enclosed space to receive from said manifold the hot air and gaseous products of combustion and discharge same into said enclosed space, encasing pipes connected to and extending from said first mentioned casing and spaced from said distributing pipes, restricted openings being provided from said casing into said encasing pipes, a first air inlet to said fan comprising a pipe leading to said fan from outside said enclosed space, a motor located in said pipe substantially in line with the axis of said pipe and coupled to drive said fan, and a second air inlet to said fan communicating with said enclosed space to effect recirculation of heated air discharged from said distributing pipes into said enclosed space;

whereby air is supplied by said fan to said first mentioned casing from which it flows through said holes into said combustion chamber and also through said restricted openings into the annular spaces between said distributing and 5 encasing pipes.

CALVIN D. MACCRACKEN.
